UNITED STATES PATENT OFFICE.

HARRY W. KEELER, OF NEW YORK, N. Y.

GOLF BAG.

Application filed October 19, 1923. Serial No. 669,535.

To all whom it may concern:

Be it known that I, HARRY W. KEELER, citizen of the United States, and resident of New York, in the county of New York and 5 State of New York, have invented certain new and useful Improvement in Golf Bags, of which the following is a specification.

This invention relates to golf bags, though it is noted that the invention is not limited 10 to golf bags nor in some respects even to bags.

One object of the invention is to provide a very serviceable bag of this kind and an efficient method of making the same.

15 Another object of the invention is to provide upper and lower rims for the bag which are sightly in appearance and which will not come off.

Another object of the invention is to provide 20 in a device of this kind an improved way of holding the bottom in place.

Other objects of the invention are to improve generally the simplicity and efficiency 25 of such bags and to provide a device of this kind which is durable, economical to manufacture and operate, and a very efficient method for making the same.

The inventive features for the accomplishment 30 of these and other objects are shown herein in connection with two forms of golf bags which, briefly stated, comprise a tubular body having a rim at the top and the bottom edge of the body. Each rim comprises a stiffening strip around the outer 35 edge face of the body and covered by a metal cuff. A shell collar is disposed around the portion of the body and cuff and covers one or more wire rings associated with said edges. The bottom of the body rests on the 40 collar.

In the accompanying drawing, showing by way of example, two of many possible embodiments of the invention,

45 Fig. 1 is a longitudinal vertical sectional view, partly in elevation, of said form of golf bag;

Fig. 2 is a plan of one form of the golf bag;

50 Fig. 3 is a fragmental vertical sectional view, on a larger scale, taken through the rim of said bag; and

Fig. 4 is a view similar to Fig. 3 of another form of the invention.

55 In Figs. 1 to 3, the bag comprises a tubular canvas or leather body 5 having strength-

ening and finishing rims 6 and 7 at the top and bottom edge of the body.

Each rim comprises a stiffening canvas strip 9 extending around the outer edge face of the body and a distance from the edge, around which is disposed a metal strengthening cuff 10 covering said stiffening strip and bent inwardly over the inner edge of the strip, as at 11, into engagement with the body. A shell collar 15 disposed around the inner face of the edge portion of the body has its outer edge portion 16 bent around the adjacent edges of the body, cuff and strip and a wire ring 20 disposed around the outer edge of the cuff. Rivets 21 passing through said collar, strip body and cuff hold the rims assembled.

The bag bottom comprises a pair of superposed stiff disk members 19 and 22, preferably of wood or fibre and frictionally fitted in the bottom of the body and resting on the top edge of the bottom collar 15 of the rim 7, the bottoms being double for providing strength with lightness of weight and resiliency.

While the parts of the bag may be assembled in any suitable way, I have found it convenient to assemble it by placing the tubular body on a mandrel and then placing the metallic cuff 10 on the edge of the body with a preformed groove in the outer edge to hold the wire ring 20. The stiffening strip 9 may be inserted between the cuff and body. Next the bottom is placed within the body against the end of the mandrel and a wire ring is assembled in the partially bent outer edge of the collar 16 and the collar with the ring in the groove is then inserted in the body with the inner edge of the collar against the bottom disk 22. The parts are then secured by spinning the collar tight on the ring and body against said bottom disk, and securing the rivets 21 through said cuff, strip, body and collar.

100 In the form of invention of Fig. 4, the tubular body 5, the stiffening strip 9 and the metal cuff 10 are the same as in Fig. 3. But in addition to the wire ring 20 around the outer edge of the cuff, I also provide a wire ring 24 around the outer edge of the inner face of the body 5, over which wires is disposed a shell collar 25 having its margins 26 and 27 respectively disposed around the inner face of the edge portion of the body 5 and the outer face of the cuff 10 and hav-

ing its intra-marginal portion 28 spun around the said wire rings 20 and 24. Rivets 31 pass through said body, cuff, strip and margins 26 and 27. The bottom 19, 22 in 5 the body rests on the edge of the inner margin 26.

The form of rim of Fig. 4 may be assembled in a manner similar to that of Fig. 3, but in the latter case I assemble a pair of 10 wire rings in the partially bent intra-marginal portion of a collar and then place the collar with its margins embracing the edge portions of the outer face of the cuff and the inner face of the body with one ring on 15 the outer edge of the cuff and the other on the inner edge face of the body, after which the collar is spun tight on said rings, cuff and body.

I claim as my invention:

- 20 1. In combination, a tubular body; a rim at the edge of the body comprising a metal cuff around the outer edge face of the body; a wire ring around the outer edge of the cuff; and a collar around the inner face of the edge portion of the body and having its outer edge portion bent around the said wire ring.
- 30 2. In combination, a tubular body; a rim at the edge of the body comprising a metal cuff around the outer edge face of the body; a wire ring around the outer edge of the cuff; and a collar around the inner face of the edge portion of the body and having its outer edge portion bent around the said wire ring.
- 40 3. In combination, a tubular body; a rim at the lower edge of the body comprising a metal cuff around the edge face of the body; a ring around the lower outer edge of the cuff; a ring around the lower inner edge of the body; and a collar around the lower outer edge portion of the cuff and around the lower inner edge portion of the body and intermediately bent over said rings.
- 50 4. In combination, a tubular canvas or leather body; a strengthening and finishing rim at the top and bottom edge of the body each comprising a stiffening canvas or leather strip around the outer edge face of the body extending a distance from the edge; a metal strengthening cuff covering said stiffening strip and bent over the inner edge of the strip into engagement with the body; a wire ring around the outer edge of the cuff; a shell collar around the inner face of the edge portion of the body and having its outer edge portion bent around the said wire ring and the adjacent edges of the body, cuff and strip; and rivets passing through said collar, strip, body and cuff; and a bottom comprising a pair of superposed stiff disk members fitted in the bottom of the body and resting on the top edge of the bottom collar.
- 60 5. In combination, a tubular body; a rim

at the edge of the body comprising a metal cuff around the outer edge face of the body; a wire ring around the outer edge of the cuff; a wire ring around the inner edge of the body; and a shell collar having its margins respectively disposed around the inner face of the edge portion of the body and the outer face of the cuff and having its intra-marginal portion spun around the said wire rings.

6. A method comprising placing a tubular body on a mandrel; assembling a wire ring in the partially bent outer edge of a collar; inserting the collar in the body with its inner edge against the inner face of the body 70 and the ring outside of the body; and spinning the collar tight on the ring and body.

7. A method comprising placing a tubular body on a mandrel; placing a metallic cuff 85 on the edge of the body having a pre-formed groove in the outer edge to hold a wire ring; placing a stiffening strip between the cuff and body; placing the bottom within the body; assembling a wire ring in the partially bent outer edge of a collar; inserting 90 the collar in the body with its inner edge against the bottom and the ring in the groove; spinning the collar tight on the ring and body and against said bottom; and securing rivets through said cuff, strip, body 95 and collar.

8. The method comprising placing a tubular body on a mandrel; placing a metallic cuff on the lower outer edge portion of said body; placing a stiffening strip between the cuff and body; placing a bottom within the body; assembling a ring on the lower outer edge of said body in the bent outer edge of a collar; and spinning the inner edge portion 100 of said collar against said bottom and tight on the lower inner edge portion of said body and tight over the lower ends of said body, cuff and strengthening strip and the bent end of the collar tight over said ring.

9. The method comprising placing a tubular body on a mandrel; placing a metallic cuff on the lower outer edge portion of said body; placing a stiffening strip between the cuff and body; placing a bottom within the body; assembling a ring on the lower outer edge of said body in the bent outer end of a collar; spinning the inner end portion of said collar against said bottom and tight on the lower inner edge portion of said body and over the lower ends of said cuff and strengthening strip and the bent outer end of the collar tight over said rims; and securing together said cuff, strip, body and collar by means passing through the cuff, strip, 115 body and collar.

10. The method comprising placing a tubular body on a mandrel; placing a metallic cuff on the lower outer edge portion of said body; placing a stiffening strip between the cuff and body; placing a bottom within the 120

- body; assembling a ring on the lower outer edge of said body in the outer intermediate bent portion of a collar; assembling a ring in the inner intermediate bent portion of said collar; and spinning the inner end portion of said collar against said bottom and tight on the lower inner edge portion of said body and the inner intermediate bend of the collar tight over the inner ring and the portions of the collar between the bends thereof tight over the lower ends of said body, cuff and strengthening strip and the outer intermediate bend of the collar tight over the outer ring and the outer end portion of the collar tight over said cuff.
11. A method comprising placing a tubular body on a mandrel; placing a metallic cuff on the edge of the body; placing the bottom within the body; assembling a wire ring in the partially bent outer edge of a collar; inserting the collar in the body with the ring on the outer edge of the cuff; and spinning the collar against said bottom and tight on the ring and body.
12. A method comprising placing a tu-
- bular body on a mandrel; placing a metallic cuff on the edge of the body; assembling a pair of wire rings in the partially bent intra-marginal portion of a collar; inserting the collar with its margins embracing the edge 30 portions of the outer face of the cuff and the inner face of the body with one ring on the outer edge of the cuff and the other on the inner edge face of the body; and spinning the collar tight on said rings, cuff and 35 body.
13. In combination, a tubular body; a wire ring around the outer marginal face of the body; a wire ring around the inner marginal face of the body; and a shell collar having its margins respectively disposed around the inner face of the edge portion of the body and the outer face of the body and having its intra-marginal portion engaging the said wire rings.

Signed at 2 East 23rd St. in the county of New York and State of New York this 15th day of October A. D. 1923.

HARRY W. KEELER.
